UNITED STATES PATENT OFFICE.

MARTIN HALLENBECK, OF ALBANY, NEW YORK, ASSIGNOR TO ALFRED BLAKER, OF NEWTOWN, PENNSYLVANIA.

IMPROVEMENT IN HARVESTERS.

Specification forming part of Letters Patent No. **83,627**, dated November 3, 1868.

To all whom it may concern:

Be it known that I, MARTIN HALLENBECK, of the city and county of Albany, in the State of New York, have invented certain new and useful Improvements in Harvesters, of which the following is a full, clear, and exact description, reference being had to the accompanying drawings, which make part of this specification, and in which—

Figure 1 represents a plan, and Fig. 2 an elevation, of my improved harvester. Fig. 3 represents a plan view of a portion of the heel end of the cutting apparatus.

My invention relates to that class of harvesters known as two-wheeled front-cut machines. Its object is to enable the cutting apparatus to conform freely to the undulations of the ground without the use of a joint in the finger-beam or shoe; and the improvement herein claimed consists, first, in a novel method of combining a main frame, oscillating with an axle supported on two wheels, with a foot-board carrying the tongue, the lifting-lever, and the driver's seat, and pivoted to the frame behind the main axle, so that the weight of the driver constantly tends to elevate the cutters and cause them to run lightly over the ground; second, in a novel method of securing the finger-beam to a shoe carrying a socket arranged transversely to the finger-beam, and rocking axially in bearings or down-hangers beneath a main frame oscillating vertically on its axle, whereby the cutting apparatus is free to conform to the undulations of the ground without the use of a joint in the finger-beam; third, in a novel method of preventing the pitman from escaping from the sickle-eye by means of an adjustable flanged slotted guard-plate on the finger-beam.

In the accompanying drawings, two driving and supporting wheels, A A', are shown as mounted on an axle, B, fixed on the main frame C, which is, by preference, made of metal. The tongue D is bolted to a socket, d, on the foot-board E, which has two lugs, e, pivoted to the frame behind the axle, so as to allow free vertical play to both the tongue and frame. By this arrangement the pull on the tongue and the weight of the driver act on the main frame in rear of the axle, and thus tend to counterbalance the pressure of the cutting ap-

paratus on the ground, and make the machine run lightly. This arrangement likewise enables me to lift the cutting apparatus easily by the lifting-lever when moving forward, and in backing the tendency is also to lift the cutters. The driver's seat F is mounted on a standard, f, secured to the foot-board. A lifting-lever, G, of well-known construction, is pivoted to the grain side of the foot-board.

Two down-hangers or stirrups, h¹, support in proper sockets a pin, h², on which a tubular socket, I, fits, and is held by a set-screw, i. This socket is rigidly secured to or cast in one piece with the shoe J, which is provided with a leading-wheel, K, of the usual form. A lever, H, has an eye on its lower end, through which the pin h² passes and bears against one edge of a slot in the socket. The upper end of this lever bears against the under side of the foot-board, and thus lifts the divider end of the cutting apparatus by rocking the socket axially on its pivot as the main frame is raised.

The finger-beam L is provided with guard-fingers and cutters of the usual construction, and is secured to the shoe by bolts l, passing through the shoe, the finger-beam, and through a block, m, which serves to guide the cutters and keep them in their proper position. By this mode of construction these parts can easily be removed and replaced.

In order to prevent the pitman-head from flying out of its socket in the cutter-bar, a flanged plate, N, is provided with a diagonal slot, n, through which a set-screw passes into the finger-beam. The flange can thus be set nearer to or farther from the sickle-eye, and, when secured in place, holds the pitman-head in the eye of the sickle without other fastening.

Internally-gearred spur-wheels O on the driving-wheels drive corresponding pinions o, provided with suitable backing-ratchets, and mounted on a counter-shaft, P, behind the main axle, and carrying a bevel-wheel, R, which drives a corresponding pinion, s, on a crank-shaft, S, turning in a box on the main axle, and in another box on the front cross-bar of the main frame. A balance-wheel, T, on the crank-shaft carries a wrist-pin, t, which drives the cutters by a pitman, u, in the usual way.

The operation of the machine is obvious. The tongue is supported by the team. The main frame oscillates freely with the main axle. The finger-beam rises and falls with the main frame, and also oscillates on the pin h^2 . When the finger-beam is raised by the driver the lever H strikes the foot-board and lifts the divider end of the cutting apparatus by turning the sleeve I on its pivot h^2 .

What I claim as my invention, and desire to secure by Letters Patent, is—

1. The arrangement, as described, for joint operation, of the tongue, the driver's seat, and the lifting-lever on the foot-board, pivoted to the main frame behind the main axle, for the purpose specified.

2. The arrangement, for joint operation, as described, of the main frame, the down-hangers h h¹, the lever H, the socket I, and the cutting apparatus.

3. The combination, as described, with the sickle-eye and pitman, of the flanged slotted guard-plate N, for the purpose specified.

In testimony whereof I have hereunto subscribed my name.

MARTIN HALLENBECK.
